UNITED STATES PATENT OFFICE.

HENRY ZIEMSS, JR., OF CHICAGO, ILLINOIS, ASSIGNOR TO CHICAGO RAILWAY EQUIPMENT COMPANY, OF CHICAGO, ILLINOIS, A CORPORATION OF ILLINOIS.

BRAKE-BEAM.

1,036,053.

Specification of Letters Patent. Patented Aug. 20, 1912.

Application filed November 4, 1910 Serial No. 500,644.

To all whom it may concern:

Be it known that I, HENRY ZIEMSS, JR., a citizen of the United States, residing at Chicago, in the county of Cook and State of Illinois, have invented certain new and useful Improvements in Brake-Beams, of which the following is a specification.

This invention relates to brake beams for railway cars, the object being to improve the 10 construction of the brake head.

In the accompanying drawings, Figure 1 is a longitudinal section through one form of brake head embodying the features of my invention. Fig. 2 is an elevation of the 15 back of the brake head, and Fig. 3 is a fragmental side elevation of said head.

The brake head may comprise a face 14 having flanges 15 at its sides, and a hub 16 lying between said flanges. The flanges 15 20 may have openings 17 therein adapted to receive the usual hanger. The hub 16 is slotted transversely as at 18 to form a yielding central portion 19 and two yielding side portions 20. An eye 21, which is connected 25 with said central portion and with the rigid portion 16^a of the hub by means of webs 22, is positioned to register with the openings 17 in the flanges 15 so that the eye will form part of the hanger-attaching means. The 30 webs 22 define between them a slot 23, so that the central portion 19 of the hub is made compressible or yielding, the eye 21 tending to draw the webs 22 together. I may provide a bolt 24 extending through the 35 webs 22, said bolt having a nut 25 threaded thereon for the purpose of positively drawing the webs 22 together and clamping the brake head upon the beam.

As will be observed, the longitudinal slot 40 between the webs 22 virtually cuts off one end of the central hub portion 19 from the body of the hub. In a similar manner, longitudinal slots 26 in the wall of the hub 16 separate the ends of the side portions 20 45 from the rigid portion 16^a of the hub to form spring clamping portions. The side portions 20 are connected together at their free end by an angular web 27, said web extending along one side of the slots 26 in 50 the hub. At the other side of said slots 26 and upon the rigid portion 16^a of the hub is an angular web 28. A bolt 29 extending through the webs 27 and 28, and having a nut 30, provides means for positively drawing 55 said webs together to clamp the side

portions 20 to the sleeve 11, and secure the brake head upon the beam. If desired, means may be provided which tend normally to hold the webs 27 and 28 close to each other, said means in this instance comprising a split ring 31 engaging said webs. The side portions 20 being connected together at one end by the web 27, said portions may be considered as a unitary clamping member, the middle portion 19 being a 60 separate clamping member. These two clamping members in the present embodiment lie side by side, and are attached at opposite ends to the body of the hub, said members therefore extending in opposite 65 directions. In this instance the free ends of said members lie at diametrically opposite points on the hub 16.

As will be seen from Fig. 2, the slots 18 are inclined and converge toward one another, thus causing the base or attached ends of the spring clamping portions 19 and 20 to be wider than the opposite ends thereof, and providing strength where strength is 70 most needed.

If desired, corrugations 32 may be formed upon a suitable portion of the inner wall of the hub 16, such as the clamping member 19, and also upon the sleeve 11, to assist in holding the brake head against rotation 85 upon said sleeve.

The sleeve 11 may have a groove 11^a therein, the ends of said groove merging on the periphery of the sleeve. A lug 33 projecting into the interior of the hub 16 90 is arranged to lie in the groove 11^a, said lug preventing movement of the brake head longitudinally of the sleeve 11, but permitting rotation of the brake head.

The interior of the hub 16 is preferably 95 somewhat smaller than the exterior of the sleeve 11, so that the hub is somewhat expanded when placed on the sleeve, or, in other words, the spring clamping portions 19 and 20 yield to permit the hub to be 100 placed upon the sleeve. If desired, a bevel surface may be formed at the end of the sleeve 16, the lug 33 riding up such surface and then dropping into the groove 11^a when the brake head is being placed upon the sleeve 11.

While I have herein described one embodiment of my invention in considerable detail for the sake of clearness, I realize 110 that various modifications may be made

within the spirit and scope of the invention, and I therefore do not limit myself to the exact construction shown and described.

5. I claim as my invention:
1. A brake head comprising a hub having an inclined slot therein extending around a portion of its wall, said slot forming a spring clamping portion which is wider at its base or attached end than at its opposite end.
  2. A brake head comprising a hub having two inclined converging slots therein, said slots forming between them a central spring clamping portion, said slots also forming a spring clamping portion at each side of said central clamping portion, said hub having longitudinal slots cutting one end of each clamping portion from the body of the hub.
  3. A brake head comprising a hub provided with two spring clamping portions, one of said clamping portions having its base or attached end at one side of the hub, and the other clamping portion having its base or attached end at the opposite side of the hub.
  4. A brake head comprising a hub having a central spring clamping portion and an oppositely extending clamping portion comprising two parts lying at opposite sides of the central portion.
  5. A brake head comprising a hub having a slot extending around a portion of its wall, said slot forming two spring clamping portions.
  6. A brake head comprising a hub having a transverse slot, said slot forming two spring clamping portions, said hub having longitudinal slots cutting opposite ends of said portions from the body of the hub.
  7. A brake head comprising a hub having a transverse slot in its wall to form two hub portions, one of said portions being connected to the body of the hub at one end of said slot, and the other portion being connected to the body of the hub at the other end of said slot.
  8. A brake head comprising a hub having two transverse slots in its wall, said slots forming a central hub portion, and a hub portion comprising two parts lying at opposite sides of the central hub portion,
9. A brake head comprising a hub having a slot running transversely through its wall to form two portions of the hub, a hanger-attaching eye, webs connecting said eye with one portion of said hub, said webs forming between them a slot connecting the interior of the hub with the interior of the eye, the other portion of the hub having a longitudinal slot therein at the opposite side of the hub from said hanger-attaching eye, a web on said other portion at one side of said slot, and a web on the hub body at the other side of said slot.
10. A brake head comprising a hub having oppositely extending spring clamping portions, an angular web at the free end of each of said portions, webs on the body of the hub lying alongside the first mentioned webs, and means for drawing the pairs of webs together.
11. A brake head comprising a hub slotted to form oppositely extending spring clamping portions connected at one end to the hub body, a hanger-attaching eye integral with the hub body and with the one end of one of said portions, and means for drawing the end of the other portion toward the adjacent part of the hub body.
12. A brake head comprising a hub circumferentially slotted to form a central spring clamping portion, and a spring clamping portion comprising two parts lying at opposite sides of said central portion, each of said latter parts being connected at one end to the hub body; a web at one end of one of said portions, a web on the hub body lying alongside the first web, a hanger-attaching eye integral with said webs, a web connecting the ends of the parts of the other one of said portions, a web on the hub body lying alongside the last mentioned web, and means for clamping the two last mentioned webs together.
- In testimony whereof I affix my signature in presence of two witnesses.
